UNITED STATES PATENT OFFICE

COMER ALONZO DAWSON, OF GREENVILLE, SOUTH CAROLINA

CABINET

Application filed June 26, 1930. Serial No. 464,000.

This invention relates to toilet cabinets, the primary object of the invention being to provide a cabinet for holding tooth-brushes, tooth paste or the like, which will permit of tooth-brushes drying readily, and at the same time will protect them against foreign matter, to the end that the tooth-brushes will be maintained in a sanitary condition.

An important object of the invention is to provide a cabinet including a plurality of vertical compartments having open bottoms, the compartments being normally closed by sliding closures, so that the brushes held therein will fall by gravity from the compartments when the closures are moved to their open positions.

A further object of the invention is to provide a cabinet including a plurality of horizontal compartments for containing tubes of tooth paste, the compartments for containing tooth paste and tooth-brushes being numbered with corresponding numbers indicating the tube of tooth paste to be used with a certain brush.

A still further object of the invention is to provide a pusher associated with the compartments for containing tubes of tooth paste, so that tubes may be ejected from the compartments, when the tubes become so small that they cannot be readily reached by the fingers, for removal.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a perspective view of a cabinet constructed in accordance with the invention.

Figure 2 is a longitudinal sectional view taken on line 2-2 of Figure 3.

Figure 3 is an elevational view of a cabinet, portions of the front wall being broken away.

Figure 4 is a sectional view taken on line 4-4 of Figure 2.

Figure 5 is a perspective view of a sliding closure, forming a part of the invention.

Figure 6 is a view illustrating a modified form of closure.

Referring to the drawings in detail, the cabinet comprises a box-like body portion indicated generally by the reference character 5, the body portion including a front wall 6 and a rear wall 7. Positioned between the front and rear walls, is a partition 8 that divides the body portion into front and rear sections, the front section being divided by vertical partitions 9 that define a plurality of transverse brush compartments 10.

The rear section is divided by horizontal partitions 11 that define a plurality of horizontal compartments for the reception of tubes of tooth paste, the compartments for the brushes and tubes being numbered so that certain tubes may be used with certain brushes.

The lower ends of the vertical brush compartments, are closed by means of the sliding closures 12 which are provided with a plurality of openings 13 that permit air to pass upwardly into the compartments, and at the same time allow water or moisture to drain therefrom.

Hooks 14 are secured adjacent to the bottoms of the compartments, which hook members receive the coiled springs 15 that are connected with the closures 12 so that when the closures are moved to their open positions, they will be moved against the action of the coiled spring to return the closures to their closed positions when they have been released.

In the form of the invention as shown by Figure 6 of the drawings, a closure is indicated by the reference character 16, which closure is provided with lateral extensions 17 disposed adjacent to the inner end of the closure. As shown, the closure 16 is narrower than the compartment closed thereby, so that spaces 18 are provided at opposite sides of the closure, the spaces accommodating the coiled springs 19 which are com-

pressed when the closure 16 is moved to its open position.

Thus it will be seen that when closures such as shown at 16, are moved to their open positions and released, the coiled springs will expand and return the closures to their closed positions. The inner ends of the partitions 11 are spaced from the side wall 20 of the cabinet, providing spaces to permit the pusher 21 to be moved upwardly therethrough, the pusher 21 being constructed of a length of wire having an enlarged end 22. This pusher rests in the vertical slot 23 of the wall 20 so that it may be moved upwardly to bring the enlarged end 22 opposite to any particular compartment, to force the tube of tooth paste from the compartment.

A hook 24 is formed at the outer end of the pusher 21, which hook is hooked over the nail 25 to hold the pusher in position.

A closure 26 closes the vertical compartment and may be lifted to permit the brushes to be inserted therein. It might be further stated that the cabinet forming the subject matter of this invention is designed primarily for use in containing tooth-brushes and tooth paste for several members of a family, the brushes being maintained in a sanitary condition at all times.

I claim:

1. A cabinet of the class described comprising a body portion, a plurality of horizontal partitions in the body portion, the inner ends of the partitions terminating in spaced relation with one side of the body portion, a pusher held within the body portion and adapted to operate through the spaces between the ends of the partitions and side wall of the body portion to force articles from the body portion.

2. A cabinet of the class described comprising a body portion, a plurality of horizontal partitions within the body portion, said body portion including a side wall having a slot formed throughout the length thereof, said partitions having their inner ends spaced from the side wall, a pusher rod disposed within the slot and having an enlargement on its inner end to pass into the spaces between the horizontal partitions to force articles therefrom, and a plurality of vertical compartments at the front of the cabinet.

In testimony that I claim the foregoing as my own, I have hereto affixed my signature.

COMER ALONZO DAWSON.
